ELECTRICAL DISCHARGE DEVICE

Erwin F. Lowry, Wilkinsburg, Pa., assignor to
Westinghouse Electric & Manufacturing Com-
pany, East Pittsburgh, Pa., a corporation of
Pennsylvania

Application July 19, 1934, Serial No. 735,986

4 Claims. (Cl. 250—27.5)

This application is a continuation in part of my copending application Serial No. 407,690, filed November 16, 1929, now Patent No. 1,997,693, for Electrical discharge devices.

5 My invention relates to electrical discharge devices and particularly to electrical discharge devices which employ electrodes operating at temperatures at which they emit electrons freely.

One object of my invention is to provide an 10 electron emissive cathode, the heating energy required by which is small relative to the magnitude of the electron emission per unit area of surface.

Another object of my invention is to provide 15 an electron emissive cathode in which the ratio of the electron emission to the heat dissipation per unit area of the cathode is relatively large.

Another object of my invention is to provide 20 an electrical discharge device with an electron emissive cathode in which the rate of heat dissipation per unit area of surface at a given operating temperature is minimized.

A further object of my invention is to provide 25 an electron emissive cathode for electrical and discharge devices which shall have a larger surface area than cathodes of the prior art, but which will require supports therefor only at its ends.

Other objects of my invention will become 30 apparent upon reading the following specification taken in connection with the drawings, in which:

Figure 1 is a view partly in elevation and 35 partly in section of an electrical discharge device having an electron emissive cathode embodying my invention;

Fig. 2 is a sectional view taken on the line II—II of Fig. 1;

Fig. 3 is a view partly in elevation and 40 partly in section of an arrangement for testing the temperature effects of various sized pleats in the cathode constructed according to my invention;

Fig. 4 is a graph of watts per square inch input in relationship to temperature of three filaments with different spacing between the pleats 45 thereof; and

Fig. 5 is a similar graph of a narrower filament with six different spacings between the pleats thereof.

It is desirable for certain purposes to provide 50 the electrical discharge devices with electron emissive cathodes having relatively large surfaces, and consequently capable of emitting large electron currents. Such cathodes are desirable both for high vacuum electrical discharge tubes 55 and for electrical discharge devices having gas-

ous atmospheres at appreciable pressures. Devices in which mercury vapor is present as an atmosphere about the cathode are examples of the later devices. Other examples are the devices containing noble gases, such as neon, argon, 5 etc. When it is attempted to insure a large electron current by extending the surface area of the cathode to large dimensions, the energy dissipated as heat from the cathode surface becomes a serious source of lost and decreased electrical efficiency. One of the principal objects of 10 my invention has been accordingly to devise methods of constructing hot cathodes which shall have relatively extensive surface areas, but which shall require only moderate amounts of power to 15 maintain them at their proper operating temperatures.

The foregoing object I achieve by constructing 20 the cathode of a relatively thin sheet material, which is so bent back and forth or pleated that a large fraction of its surface is so positioned that it faces other portions of its surface. In this way, the heat radiated from the first-mentioned portion of the surface is absorbed by some other portion of the surface and 25 the amount dissipated to the surrounding surfaces and lost entirely is relatively small. Thus the heating current has to supply only the relatively small losses last-mentioned, and the amount of cathode heating power required to maintain the 30 cathode at its operating temperature is minimized.

I have also discovered that the spacing between adjacent pleats very materially affects the heating efficiency and that this spacing should be less than the depth of the pleat. The same 35 consideration requires that the width of the filament be greater than the spacing between the pleats. The pleat will thus take the form of a deep pocket from which the electron current is started with a maximum of heating efficiency. 40 Due to the neutralization of the space discharge by the positive ions in the gaseous atmosphere surrounding the cathode, there is no difficulty in obtaining electrons from these deep pleated pockets.

I also desire to have this cathode structure such that it will maintain its shape during the 45 operation of the device and yet have a minimum amount of support therefor so that the heat from the filament will not be dissipated by contact with a large and relatively cool supporting area. To accomplish this object, I construct my cathode of a thin ribbon of an alloy of cobalt, nickel and ferro-titanium described in my copending application Serial No. 144,911, filed October 28, 1926. 50 55

As described in this copending application, the alloy constitutes 80% to 95% of cobalt and nickel with the nickel ranging from 5% to 95%, and the cobalt ranging from 5% to 95% of the total percentages of these two materials. The ferro-titanium acts as a deoxidizer in the alloy and comprises from 5% to 20% of the total. This material is commonly known by the trade-mark "Konal". Due to the very high hot tensile strength of this alloy, a cathode in its ribbon form can hold its shape under the high operating temperature, and in certain forms this cathode will only require supports at each end thereof. I prefer to use the Konal alloy as a core material and 15 to coat the core with a barium and strontium oxide coating to provide the electron source.

In Figs. 1 and 2 is disclosed a preferred form 20 of my cathode in which a metallic ribbon 16 is folded into deep pleats, as disclosed more particularly in Fig. 2. The spacing 11 between the pleats is very small and preferably much smaller than the width 12 of the ribbon or the depth 13 of the pleats. As previously mentioned, this cathode is preferably formed of a core of cobalt, 25 nickel and ferro-titanium with a coating of barium and strontium oxides thereover. Due to the strength of this material at operating temperature, only two supports 14 and 15 are required for this ribbon and these supports also act as 30 lead-in wires for the ends of the cathode structure. Within the container 16 is a gaseous atmosphere which may be of mercury vapor or one of the noble gases. At one end of the container is the anode 17 to form the familiar two-electrode 35 rectifier tube. If desired, one or more grids may be inserted between the anode and the cathode to form the familiar grid-controlled glow-discharge tube.

In order to test out the effect of the relative 40 spacing 11 of the pleats, I tested out the efficiency of my cathode structure with various distances between the pleats in the manner illustrated in Fig. 3. A series of pleated or crimped filaments were constructed having the same depth of fold 45 but with varied spacings between the consecutive surfaces thereof. A very small hole 20 of about 55 mils is drilled from one end 21 of the filament through the center portion to the middle 22 of the cathode structure, so that the middle 50 portion of the filament was exposed from one side of a cathode structure. The filament was then mounted in a glass vacuum tube 23, fitted with a ground glass joint 24 on a standard 25. The tube had a connection 26 to a vacuum pump. 55 When a high vacuum had been attained within the tube, the filament was raised to a red heat by current passing through the connections 27 and 28. An optical pyrometer 30 was trained upon the central hot portion 22 of the filament, 60 and pyrometer readings were taken of the central portion of the filament because it was least affected by the colder supports and outside radiation. The power was varied, using the current as a measure, while the voltage was taken directly 65 from leads 31 and 32 welded on the filament near the supports. Readings were taken for each change of current. The visibility or actually the absorption of the glass was measured by first obtaining a temperature reading of the filament 70 33 in a small bulb 34 placed directly in back of the tube in a line that just skims across the top of the heavier filament within the tube, therefore recording the apparent brightness of the bulb viewed through two walls of glass. The 75 bulb was shifted to one side in such a way that

its distance from the pyrometer was unchanged and no intervening medium between them. Half the difference between readings when plotted against the reading temperature gives the correction to be added for absorption. 5

Readings were first obtained on filaments made of nickel, cobalt, and ferro-titanium ribbon 12 inches long by .75 inch wide and .02 inch thick. The pleats were respectively $\frac{1}{16}$, $\frac{1}{8}$ and $\frac{3}{16}$ inch wide, and the results are plotted in Fig. 10 4, disclosing the watts per square inch input for the temperature in degrees centigrade. The depth of the fold or pleat was one inch as disclosed on the side of Fig. 4.

The test was also made with a filament 12 15 inches long, .5086 inch wide, .0125 inch thick and folded into deep pleats one inch in depth as disclosed in the right-hand portion of Fig. 5. Fig. 5 shows the graphs for spacing $\frac{1}{16}$, $\frac{1}{8}$, $\frac{3}{16}$, $\frac{1}{4}$, $\frac{5}{16}$, and $\frac{3}{8}$ inch, respectively, between the 20 sides of the pleats.

An examination of the curves in Figs. 4 and 5 will disclose the increased efficiency produced by my cathode with very deep pleats, whose depth is greater than the width of the ribbon and the 25 spacing between the sides of the pleats. I prefer to make this spacing as small as possible in order to have as great an area of electron emitting surface incorporated in a very small area because 30 this close spacing of the sides of the pleat pockets therein approaches a black body effect in its heat radiation characteristic.

In accordance with the patent statutes, I have disclosed a particular embodiment of my invention, but it will be recognized that this is intended to be only illustrative and that the broad principle thereof will be capable of alternative embodiments which will be evident to those skilled in the art. I desire, accordingly, that the claims shall be given the broadest construction 40 of which their terms are susceptible in view of the prior art. 35

I claim as my invention:

1. A cathode adapted to emit electrons freely 45 when heated comprising a deeply pleated sheet member of essentially a nickel-cobalt alloy containing ferro-titanium, and supports for said member only at its ends.

2. A cathode adapted to emit electrons freely 50 when heated comprising a thin metallic ribbon having continuous rectangular folds therein, the maximum distances between opposing surfaces of the same fold being less than the depth of the fold and less than the width of the ribbon, and supports for said ribbon only at its ends. 55

3. A cathode adapted to emit electrons freely 60 when heated comprising a thin metallic ribbon composed essentially of a nickel-cobalt alloy containing ferro-titanium, said ribbon having continuous rectangular folds therein, the maximum distances between opposing surfaces of the same fold being less than the depth of the fold, and supports for said ribbon only at its ends. 65

4. An electrically heated conductor in the form 70 of a sheet member of essentially a nickel-cobalt alloy containing titanium, and means for conducting current to the ends thereof and for supporting said conductor, the length of the conductor between the center of gravity of the portion thereof intervening between said points of support and the nearest point of support thereto being large compared with the straight line distance between said center of gravity and said nearest point of support. 75
